(57) CLAIM

The ornamental design for a golf club organizer, as shown and described.

DESCRIPTION

FIG. 1 is a perspective view of a golf club organizer showing my new design.

FIG. 2 is a front elevational view thereof.

FIG. 3 is a rear elevational view thereof.

FIG. 4 is a left side elevational view thereof.

FIG. 5 is a right side elevational view thereof.

FIG. 6 is a top plan view thereof.

FIG. 7 is a bottom plan view thereof; and,

FIG. 8 is a perspective view thereof.

The broken lines in FIGS. 1, 6 and 8 represent the portions of the design that form no part of the claim. The broken lines of FIG. 8, showing golf clubs stored on the golf club organizer, illustrate the design in use and form no part of the claim.
